(57) **CLAIM**

The ornamental design for a display screen with transitional graphical user interface for image-printing order-receiving terminal, as shown and described.

DESCRIPTION

FIG. 1 is a top, front and left side perspective view of a display screen with transitional graphical user interface shown in the environment of an image-printing order-receiving terminal, showing my new design;

FIG. 2 is a front view of the display screen of FIG. 1, shown enlarged and isolated from its environment for clarity of disclosure, showing the first image in a sequence; and, FIG. 3 is a front view thereof, showing the second image in a sequence.

The subject matter in this patent includes a process or period in which an image changes into another image. This process or period forms no part of the claimed design.

The broken lines illustrate portions of a graphical user interface, and, in FIG. 1, an image-printing order-receiving terminal as the environment of the claimed design. The broken lines form no part of the claimed design.
